UNITED STATES PATENT OFFICE.

CHARLES B. MOORE, OF EVANSTON, ILLINOIS, ASSIGNEE, BY MESNE ASSIGNMENTS,
TO AMERICAN ARCH COMPANY, OF NEW YORK, N. Y., A CORPORATION OF DELA-
WARE.

LOCOMOTIVE-BOILER FURNACE

1,138,035.

Specification of Letters Patent.

Patented May 4, 1915.

Application filed December 18, 1911. Serial No. 666,342.

To all whom it may concern:

Be it known that I, CHARLES B. MOORE, a citizen of the United States, and a resident of the city of Evanston, county of Cook, and State of Illinois, have invented certain new and useful Improvements in Locomotive-Boiler Furnaces, of which the following is a specification.

My invention relates to improvements in locomotive boiler furnaces and has particular reference to improvements in refractory baffle or deflecting walls, sometimes called arches, for fireboxes of locomotive boilers.

The general objects of my invention are to provide an improved refractory arch which may be easily and quickly installed in locomotive fireboxes, which are provided with circulating tubes; to provide an arch which shall be of comparatively light weight and low cost; to provide an arch which shall be adapted for easy repair and parts of which may be removed to afford easy access to the firebox side sheets; and to provide an arch of a form that will materially assist in admixing, commingling and igniting the firebox gases and combustibles.

A special object of my invention is to provide a system of arch construction whereby arches, having the characteristics herein outlined, can be readily, easily and cheaply installed in locomotive boiler fireboxes provided with circulating tubes and in which the spacing of the tubes is not exactly equal, or the same throughout the extent of the arch.

A further feature of my improvement consists in the convenience with which arches having the above characteristics can be constructed in fireboxes of various widths and having different spacings of tubes with the use of substantially identical bricks. In other words, my invention contemplates the building of arches in various boilers by the use of bricks or slabs, all of which have substantially the same form and dimensions.

My invention consists in the several improvements and various constructions and combinations of parts whereby the above objects and features are obtained and preserved together with others hereinafter appearing, and all as hereinafter fully described in reference to the accompanying drawings and as particularly pointed out in the appended claims. In said drawings

which form a part of this specification, I have illustrated a preferred form of my invention together with a modified form thereof.

In said drawings; Figure 1 is a vertical central longitudinal section of a locomotive firebox equipped with an arch embodying my invention, in a preferred form or structure the section being on the line 1—1 of Fig. 2; Fig. 2 is a longitudinal horizontal section of the firebox on the line 2—2 of Fig. 1 and showing a top plan view of the arch; Fig. 3 is a partial vertical transverse section of the firebox on the line 3—3 of Fig. 1; Fig. 4 is a detail transverse section of the arch on the line 4—4 of Fig. 1; Fig. 5 is a perspective view of a single brick.

My invention may be embodied in arches of varying construction and located in different positions in the firebox. I have limited the illustration of my invention to so-called front arches. It should be understood, however, that my invention is not limited to this specific form and location of arch.

A locomotive boiler firebox as shown in the drawings consists of a flue sheet 2, side sheets 3—3, a crown sheet 4 and a rear sheet 5. The firebox is provided at its lower end with a grate 6. Flues 7 lead forward from the flue sheet and the rear sheet is provided with a fuel door or opening 8. The firebox as illustrated is provided with four inclined circulating arch tubes 9, the same being arranged substantially parallel with the side sheets of the firebox and inclined forwardly and downwardly from the upper portion of the rear sheet to the lower portion of the flue sheet and serve to increase the circulation or flow of water between the front and rear water legs of the boiler. It is usually intended that the spacing of the tubes in the firebox be substantially equal, at least to the extent that they serve as supports for the arch. However, on account of the spacing of the stay bolts or for other reasons it frequently occurs that these tubes are not spaced equally both in relation to themselves and to the side sheets of the firebox and a particular feature of my invention resides in an arch brick so formed that it may be placed upon and retained in position by the tubes and will serve equally well in positions in which the tubes vary considerably

in their spacings, as well as where the spacing of the tubes is equal throughout the extent of the arch.

A so-called front arch usually occupies an inclined position in the forward end of the firebox extending substantially from side to side thereof and having its forward end in abutment with or arranged in close proximity to the flue sheet. The function of such arches is to obstruct the flow of the firebox gases in their passage from the grate to the flues and to deflect them out of their course, causing them not only to flow backward and forward through the firebox but also to be retained in the firebox a sufficient time for complete combustion to take place. The deflection of these gases and their consequent retention in the firebox results in an even distribution of the heat of combustion throughout the interior surface of the firebox and particularly throughout the length of the crown sheet. The deflection of the gases further results in the breaking up and admixing the streams of gases and I add to this effect by providing the arch with a plurality of subsidiary gas deflecting surfaces arranged in various planes, whereby the body of flowing gas is not only deflected generally, but the various portions thereof are caused to intermix and commingle whereby substantially perfect combustion is attained in the firebox. Refractory arches which are light in construction and arranged as described, soon attain incandescence and thereby assist in the ignition of the gases and the other combustibles and I greatly enhance this effect of the arch by providing the under surface of the arch with many comparatively thin ribs or depending portions. The arch, as illustrated, consists of a plurality of transverse rows of bricks, each row comprising a number of bricks *c* which are arranged to be supported upon adjacent tubes or upon a tube and the adjacent side sheet. These bricks are limited in size by the fact that they should not be too heavy to be easily handled and placed in position and should be small enough to be readily passed through the fuel door into the firebox. The bricks *c* are substantially rectangular in shape and their length in a general sense is determined by the spacing of the tubes, but they are so formed that they may be used in connection with tubes, the spacings of which vary to a considerable extent. The ends *c*^x of the bricks *c* which rest upon the tubes are cut away or angled, the length of the lower face of each brick being considerably shorter than the length of the back or upper face of the brick. The transverse section of these bricks is consequently wedge shaped and the bricks having considerable thickness they are adapted to fit between tubes whose spacings vary from a fixed standard. The bricks in any special

installation are simply lowered between adjacent tubes until they find a resting place thereon. The lower faces of the bricks are provided with gas mixing pockets or cavities, and as clearly illustrated in Figs. 1 70 and 4, the inclosing walls or surfaces of these pockets or cavities are inclined relatively to the upper and lower faces of the brick, and the arch is thereby provided with many gas deflecting surfaces arranged in 75 different angularly disposed planes. These pockets or cavities and the inclined ends of the bricks assist in the main action of the arch in commingling and admixing the firebox gases. When installing an arch in accordance with my invention, I first arrange a transverse row of the arch bricks *c* resting them upon the tubes and spacing them from the flue sheet by means of spacing blocks or bricks *b* on the lower ends of said tubes. I 80 then place a second transverse row of the arch bricks higher up in the firebox resting upon the arch tubes and against the first row. The arch is completed by placing further transverse rows in position above those already placed, sufficient in number to construct an arch of the desired height or length. This height or length is determined by the shape of the firebox and the action of the draft therein, usually extending to 90 about the longitudinal center of the firebox. 95

In Figs. 3, 4 and 5 I have illustrated the bricks, *c*, in detail. The general form and purpose of the brick is described above. The under surface, of the brick, *c*, is provided with the gas mixing pockets or recesses *c*¹ in the form of two open ended pockets or cavities divided or separated by a thick central portion or transverse rib *c*². The tops *c*³ of these pockets are curved upwardly and outwardly from the lower face of the rib *c*², to the opposite ends of the brick. This construction provides the brick *c* with side flanges *c*⁴ at each end, and consequently the tubes upon which these 100 bricks rest are exposed to the action of the firebox gases. The inclined ends of the bricks *c* and the upwardly and outwardly curved tops *c*³ of the open ended pockets *c*¹ 105 tend to direct the flow of the firebox gases directly against the sides of the circulating tubes 9 and this action besides aiding in the commingling of the gases adds very much to the rapidity of the transmission of heat 110 through the walls of the tubes to the contained water. 115

The arch being built up of a plurality of individual bricks each one of which is supported independent of the others, provides a structure from which any one or number 120 of bricks may be removed easily without disturbing the rest of the arch when it is necessary to replace broken bricks or repair the arch. Further the end bricks of the rows 125 can be removed without disturbing any 130

other part of the arch when it is desired to repair the side sheets or the stay bolts.

One advantage peculiar to this improved construction of arch is that the end bricks of the transverse rows serve to steady the arch or lock it against lateral movement in the firebox and yet on account of the arch being built up of a plurality of comparatively small members it is as a whole more or less flexible and can accommodate or adjust itself to any slight differences of dimensions of the firebox due to contraction or expansion of the firebox sheets on account of varying temperatures and pressures. When the firebox expands the separate bricks of the arch settle between the tubes and when it contracts these bricks are, in a sense, automatically raised on the tubes on account of their inclined ends.

Having thus described my invention I claim as new and desire to secure by Letters Patent:

1. A locomotive boiler firebox containing a plurality of arch supporting tubes, in combination with a plurality of transverse rows of arch bricks supported by said tubes, said rows extending from side to side in the firebox and arranged side by side upon the tubes, each said brick having oppositely inclined flat ends, the upper face of each brick being longer than the space between the supports upon which it rests whereby the brick depends between its supports and is thereby held against lateral movement in the firebox, and each said brick having oppositely disposed open ended recesses in its underside, adapted to deflect the firebox gases against the supports upon which the brick rests, substantially as described.
2. A locomotive boiler firebox containing a plurality of arch tubes, in combination with a front arch extending from side sheet to side sheet, and composed of a plurality of substantial identical bricks, each said brick being flat and oppositely beveled at its ends where it rests upon its supports and whereby it is held against lateral movement in the firebox, and each said brick being provided

on its underside with oppositely disposed curved bottomed open ended recesses adapted to deflect the firebox gases laterally against the supports upon which the brick rests.

3. A locomotive boiler firebox containing inclined arch tubes, in combination with a longitudinal row of substantially identical bricks resting upon a tube and wedgingly engaging the adjacent side sheet of the firebox, each said brick having its ends oppositely beveled, and being provided on its under surface with a gas-mixing pocket or cavity having a curved bottom and an open end adapted to deflect the firebox gases against the side sheet of the firebox, substantially as described.

4. An arch brick for use in a locomotive boiler furnace provided with arch tubes spaced apart, the brick being adapted to rest upon the tubes and having its transverse ends which contact with the tubes flat and oppositely beveled, two oppositely extending recesses in the bottom of the brick having upwardly and outwardly curved bottoms and open ends whereby they are adapted to deflect the firebox gases laterally against the sides of the tubes upon which the bricks rest.

5. A locomotive firebox arch-brick, composed of refractory material, having ends formed for engagement with arch tubes and in its bottom provided with oppositely extending cavities or recesses which open through respective ends of the brick, for the purposes described.

6. A locomotive firebox arch-brick, composed of refractory material, having ends formed for engagement with arch tubes and in its bottom provided with grooves which open through respective ends of the brick, there being a thick portion which separates said grooves, for the purposes described.

In testimony whereof, I have hereunto set my hand, this 5th day of December, 1911, in the presence of two subscribing witnesses.

CHARLES B. MOORE.
